UNITED STATES PATENT OFFICE.

KYLE E. STANT, OF CONNERSVILLE, INDIANA, ASSIGNOR TO THE STANT MACHINE COMPANY, OF CONNERSVILLE, INDIANA, A CORPORATION OF INDIANA.

RADIATOR CAP.

Application filed June 23, 1927. Serial No. 200,861.

My invention relates to radiator caps. It is the object of my invention to provide a radiator cap consisting of a stationary annular portion and a hinged cover so hinged 5 to the stationary portion that it will not only have the ordinary hinge movement with respect thereto but will be permitted a limited lateral movement on the hinge so as to effect a locking between the inter-engaging portions of the stationary portion and the cap cover.

It is a further object to provide a sealing member of a resilient water-absorbing material which is resistant to acids, alkalis and 15 heat, and so confine and arrange such sealing member that this absorption of moisture and its expansion will be so confined and directed in the proper direction that its properties will be taken advantage of and so directed 20 as to improve the sealing effect the longer the material is used.

It is my further object to provide specifically a vulcanized fiber sealing ring, which has the proper properties and resiliency, resistance to corrosives and heat not found in 25 rubber and other similar materials, for use as a sealing ring and to locate it in an open top metal channel so that it can only expand upwardly to improve the sealing effect between the cap cover and body.

Referring to the drawings:

Figure 1 is a section on the line 1—1 of Figure 2;

Figure 2 is a front elevation partially 35 broken away to show the locking arrangement;

Figure 3 is a section on the line 3—3 of Figure 1;

Figure 4 is a top plan view with the cover 40 cap in raised position;

Figure 5 is a front elevation with the cover cap in elevated position so as to disclose the interior arrangement of the cover cap.

Referring to the drawings in detail, 1 is a 45 stationary body portion internally threaded at 2 for attachment to the radiator. This body is provided with an internally extending flange 3 surrounding the interior passage-way 4. Such flange is provided with a shoulder 5 which forms one wall of a groove 6, the other wall of which is formed by the shoulder 7 of the upper portion of the body 1. In this groove is located a fiber ring 8. The ring is confined on three sides but is free on its upper 55 side to expand upwardly.

Such a fiber ring of vulcanized fiber absorbs moisture, is resistant to heat, alkalis and acids, such as are commonly found in radiator constructions and operation, but when so heated and moistened has a tendency 60 to expand. By confining a ring in a groove and permitting it only to expand upwardly the result is that the sealing effect of this ring is improved and the more it expands the better the seal.

The resilient diaphragm 9 engages with this sealing ring and accommodates itself to the height of the ring. Such resilient diaphragm is carried on the depending annular ring 10 and a central sleeve 11 depending 70 from the cap cover 12. The stud 13 serves to retain the parts in operative position. This cap cover 12 is provided with a depending hinge lug 14. This lug has an aperture therethrough designated 15 which is broader 75 than it is deep so that the cap cover may move laterally with respect to the stationary portion 1. The attachment of the cap cover with respect to the stationary portion is through the hinge pin 16 carried in the adjacent ears or spaced ends of the ring 17 formed as an annulus on the upper edge of the body 1. The body 1 is attached to the radiator through the set screw 18 in the usual manner.

The ring 17 has an upwardly and outwardly projecting hook member 19 engaging with an inwardly projecting hook member 20 carried on the cap member. These two hooks are adapted to interlock or unlock by 80 the lateral movement of the cap cover with respect to the stationary body 1, which lateral movement is provided for by the elongated slot 15 which is elongated and widened in a horizontal plane to permit of this lateral 85 movement and vertical movement of the cap cover about the point of hinging of the cap cover to the stationary body portion 1.

It will be understood that I desire to comprehend within my invention such modifications as may be necessary to adapted it to varying conditions and uses.

Having thus fully described my invention, what I claim as new and desire to secure by Letters Patent, is:

1. In a radiator cap, a stationary portion, a cap cover adapted to be hinged thereto, and means of connecting said cap cover and stationary portion so as to provide both for vertical hinged movement of the cover and lateral movement of the cover.

eral movement with respect to the stationary portion.

2. In a radiator cap, an annular body portion, a cap cover adapted to be hinged thereto, a hinge pin for connecting the cap cover to the body member, said parts being so arranged as to permit of lateral movement of the cap cover with respect to the hinge pin and rotating movement with respect thereto.

3. In combination in a radiator cap, of an annular stationary portion, an interlocking laterally movable pivoted cap member pivoted thereon, and a hinge connection between the stationary portion and the cap member constructed to permit horizontal and vertical swinging motion about a single point.

4. In combination in a radiator cap, of an annular stationary member having a portion of one side cut away, a cap having a depending hinge member extending into said cut-away portion, said depending member having a lateral elongated slot therein, a hinge pin in said stationary member and passing through said elongated slot to form a loose connection and interlocking means on said cap cover and stationary member for locking the two together by lateral movement of one with respect to the other.

5. In combination in a radiator cap, of an annular stationary member having a portion of one side cut away, a cap cover having a depending hinge member extending into said cutaway portion, said depending member having a laterally elongated slot therein, a hinge pin passing through said stationary

member and said elongated slot to form a loose connection and interlocking means on said cap cover and stationary member for locking the two together by lateral movement of one with respect to the other, said interlocking means consisting of an inwardly extending finger on the cap cover, and a spaced outwardly extending finger on the stationary member to engage the cap finger whereby said interlocking means is concealed. 45

6. In a radiator cap, a stationary member, a cap cover adapted to be hinged thereto, and means of connecting said cap cover and stationary portion so as to provide both for vertical hinged movement and lateral movement with respect of one to the other about a single point, and means carried by the stationary member to provide for a smooth and close fit between the stationary member and the cap cover when the cap cover is in closed 50 55 position.

7. In a radiator cap, an annular body portion, a cap cover adapted to be hinged thereto, a hinge pin for connecting the cap cover and the body member to one another, said parts being so arranged as to permit of lateral movement of the cap cover with respect to the hinge pin and vertical rotating movement with respect thereto, a fiber ring carried by said stationary member and engaged 60 65 by said cap cover to form a smooth and close connection therebetween.

In testimony whereof, I affix my signature.

KYLE E. STANT.
